UNITED STATES PATENT OFFICE.

RAYMOND ELMER STERLING AND HARRY WILLIAM BOCKHOFF, OF RICHMOND, INDIANA, AND ETHAN CHARLES HOPKINS, OF NORWOOD, MASSACHUSETTS, ASSIGNORS TO THE NATIONAL AUTOMATIC TOOL COMPANY, OF RICHMOND, INDIANA, A CORPORATION OF INDIANA.

SPINDLE BUSHING PLATE.

Application filed February 26, 1924. Serial No. 695,213.

This invention relates to machine-tools and more particularly to machine-tools having a plurality of revolving spindles; such as, for instance, multiple drilling-machines.

Heretofore, difficulty has been experienced in the operation of these machines due to the spindles flexing somewhat when subjected to certain strains during the drilling operation. This flexing of the spindles reduces the precision with which these machines are supposed to operate and has been the cause of producing imperfect work.

This invention has for an object to provide, in machines of this type, simple and efficient means for maintaining the spindles in their proper positions and preventing them from flexing when subjected to the strains incident to the working operation; and also to provide means for effectively lubricating the spindle bearings which means shall require the attention of the operator only at great intervals.

A still further object of the invention is to provide an essentially simple and inexpensive lubricating device which is self-acting, is sealed against leakage, and which admits of being very easily made to satisfy the diversified requirements of a number of drill spindles, which must, to meet various conditions, be arranged in a great variety of positions.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is a side-elevation of a portion of a multiple drilling-machine embodying the

present invention. Fig. 2 is an enlarged side elevation partly in section of a portion of Fig. 1. Fig. 3 is a horizontal sectional view taken on the line 3—3 of Fig. 1 with a portion of the reservoir cover-plate broken away better to illustrate the invention. Fig. 4 is a modification showing an alternative means for supporting the element adapted to hold the spindles against displacement.

Referring more particularly to the drawings, the invention is shown embodied in a multiple drill comprising the usual drill-supporting head 1, mounted for vertical bodily movement upon a suitable standard 2 and provided with a plurality of drill-supporting spindles 3.

In a manner common to machines of this type, these spindles are simultaneously rotated from a suitable actuating shaft 4 and are held in any desired position of horizontal adjustment by suitable spindle-arms *a* (of which only two are shown) adjustably secured to the underside of the head 1.

In the drawings the spindles are shown equally spaced and located in circular formation, merely for the purpose of illustration, but it is to be understood that they may be adjusted to any positions, within certain limits, to suit the nature of the work to be produced. As the actuation and adjustment of the spindles is old and well understood, detailed illustration and description thereof is deemed unnecessary.

The free ends of the spindles necessarily depend below the spindle-arms and are subject to certain strains, during the drilling operation, which have heretofore produced lateral displacement of the spindles and the drills carried thereby, with the result that the work produced has been more or less imperfect.

As before stated, an object of this invention is to eliminate this lateral displacement, and to that end there has been provided, between the drill-supporting head and the lower ends 5 of the spindles, a rigid plate 6, preferably, but not necessarily, secured upon

2 a rigid supporting post 7, integral with the head 1, and co-axial with the shaft 4. The plate 6 is provided with a series of apertures 8 located in any formation to suit the 5 work to be produced and adapted to receive bushings 9 which form bearings for the lower ends of the spindles. It will be observed that any strain applied to any one of the spindles will, by means of the rigid plate 10 6, be transmitted to the rigid supporting post 7, whereby the drill under strain will be held against lateral movement. The plate 6 is formed in its upper face with a depression which provides a reservoir 11 for the 15 reception of suitable lubricant for the spindle bearings. Beneath the bushings 9 and within suitable cavities 12 in the plate 6 are held packing rings 13 which preferably are in the form of felt washers. Cover plates 20 14, attached by means of screws 15 to the plate 6, act to hold the packing rings in place and compress them against the spindles, thus forming oil-tight joints which prevent a leakage of the lubricant. The reservoir 11 25 is closed by a cover-plate 16, secured by screws 17 to the plate 6, and is provided with suitable apertures 18 for passage of the spindles 3.

As illustrated in Fig. 4, the plate 6 may, 30 if desired, be carried by arms 19 adjustably secured to the flange *f* of the head 1, instead of being secured to the post 7.

From the foregoing it will be observed 35 that there has been provided a simple and efficient means for eliminating the strain to which the spindles are subjected; thus preventing them from lateral displacement. Also, that applicant has provided means for lubricating the spindle bearings which will 40 not require the attention of the operator except at very great intervals when it is desired to renew the lubricant.

Without further analysis, the foregoing 45 will so fully reveal the gist of this invention that others can, by applying current knowledge, readily adapt it for various utilizations by retaining one or more of the features that, from the standpoint of the prior art, fairly constitute essential characteristics 50 of either the generic or specific aspects of this invention, and, therefore, such adaptations should be, and are intended to be, comprehended within the meaning and range of equivalency of the following claims.

55 Having thus revealed this invention, we claim as new and desire to secure the following combinations and elements, or equivalents thereof, by Letters Patent of the United States:

60 1. In a multiple drilling machine, a head providing a plurality of individual supports; a rotatable spindle carried by each support; and auxiliary means located adjacent the tool-holding ends of said spindles 65 and providing bearings for said spindles for

holding the spindles against relative lateral movement.

2. A machine-tool of the type described, combining a movable head provided with a multiplicity of individual supports, a rotatable spindle journaled in each support, and means common to all of the spindles and carried by the head for holding the spindles against lateral movement. 70

3. A machine-tool of the type described, combining a head provided with a multiplicity of individual supports, a rotatable spindle journaled in each support, and means comprising a rigid plate carried by said head and formed with bearings for all of the spindles for holding the spindles against lateral movement. 80

4. In a machine-tool of the type described, a head provided with a multiplicity of individual supports, a rotatable spindle journaled in said support, a supporting post, secured to said head, and a rigid plate carried thereby and provided with bearings for all the spindles; said post and plate affording means for bracing the spindles 90 against lateral movement.

5. In a machine-tool of the type described, a movable head, a multiplicity of individual supports adjustably mounted on said head, a rotatable spindle journaled in each of said 95 supports and means including a rigid plate secured to the head and cooperating with the spindles for preventing lateral displacement of any of the spindles.

6. In a machine-tool of the type described, 100 a head, a plurality of rotatable spindles carried thereby, a rigid plate located beneath the head and provided with bearings for all of the spindles, a lubricant reservoir formed in said plate and connecting said bearings 105 and means for preventing the lubricant from escaping from said reservoir.

7. A machine-tool combining a head, a rotatable spindle carried thereby, a bearing for the lower end of the spindle and spaced 110 from said head, means for lubricating said bearing including a lubricant reservoir through which the spindle passes and means for preventing escape of lubricant from said reservoir. 115

8. A machine-tool combining a head, a rotatable spindle carried thereby, a bushing plate located intermediate the head and the end of the spindle and provided with a cavity 120 and a bearing for said spindle, means for lubricating said bearing including a lubricant reservoir formed in said plate and providing the lubricant bath around the spindle, and a packing ring located in said cavity for preventing the escape of lubricant 125 from said bearing.

9. In a machine-tool of the type described, a head, a rotatable spindle carried thereby, a spindle bushing plate located intermediate the head and the end of the spindle and pro- 130

vided with a cavity and a bearing for said spindle, means for lubricating said bearing including a lubricant reservoir in said plate and forming a bath of lubricant engaging the spindle, a cover for said reservoir, a packing ring located in said cavity, and a cover-plate adapted to compress said packing-ring around said spindle to effect an

oil-tight joint and prevent escape of lubricant from said bearing. 10

In witness whereof, we have hereunto subscribed our names.
